by Nissen & Crane *Atkins*

UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING AND LOADING MACHINE.

Application filed October 24, 1921, Serial No. 509,979. Renewed November 25, 1927.

My invention relates to mining and loading machines, and one of its objects is the provision of improved and efficient mechanism for dislodging coal from mine veins 5 and transferring the dislodged coal to loading position.

A further object of the invention is the provision of improved feeding mechanism particularly adapted to a continuously forward moving dislodging mechanism having 10 an arcuate path of travel along an upright mine wall.

Another object of the invention is the provision of arc wall dislodging mechanism and 15 improved anchoring apparatus combined therewith.

A further object of the invention is the provision of a joint between the arc wall dislodging mechanism and the main frame 20 of the machine to enable such arc wall dislodging mechanism to operate along the side walls of the mine chamber.

A further object of the invention is the provision of a hydraulic system of anchoring 25 the wall jacks for controlling the position of the mining machine during the operation of the arc wall dislodging mechanism.

Other objects of the invention will appear 30 hereinafter, the novel features and combinations being set forth in the appended claims.

Referring to the accompanying drawings, Fig. 1 is an elevational view of my im- 35 proved machine;

Fig. 2 is a longitudinal sectional elevation of the mining and loading machine shown in Fig. 1;

Fig. 3 is a plan view of the mining and 40 loading machine;

Fig. 3^a is a sectional elevation on the line 3^a—3^a of Fig. 3, looking in the direction of the arrows;

Fig. 4 is an end elevational view of the 45 dislodging tools shown at the right hand end of Fig. 3;

Fig. 5 is a sectional elevation on the line 5—5 of Fig. 2, looking in the direction of the arrows;

Fig. 6 is a diagrammatic plan view to 50 illustrate the various positions of the dislodging mechanism as permitted by the joint between the latter and the frame on which the motor is mounted; and

Fig. 7 is a diagrammatic illustration of 55 the hydraulic system for operating the various hydraulic devices including the anchoring and wall jacks.

In Fig. 2 a main frame 8 is shown as supporting the operating motor 9. The main frame 10 of this motor may be secured to the frame 8 and the rear frame 11 as shown in Fig. 1, so that in reality the motor frame and the rear frame 11 are rigidly connected to the main frame 8 and become a part 65 thereof.

Extending forwardly from the main frame 8 is an extension 8', as shown in Fig. 2. Mounted on this extension 8' is a casting 12, the latter having arcuate movement on an 70 upright axis relatively to the extension 8'. By referring to Fig. 3 it will be seen that the casting 12 is provided with a plurality of vertical openings 13, through which bolts 14 may be inserted and fitted into recesses 15 in the frame 8, so that when the casting 12 is adjusted in position it may be held rigidly against the frame 8 against turning on the upright axis. In addition to the vertical bolts 14, radial bolts 15 may also be provided for insertion into radial recesses 16, as shown in Fig. 3, so as to firmly lock the casting 12 to the frame 8 when relative adjustment has been secured. The radial bolts 15, however, are extended through the frame 8 into recesses in the rearward portion 75 17 of the base frame 18, as shown in Figs. 1 and 3.

Secured to the base frame 18 is a casting 19 as shown in Fig. 2, which affords a bearing 20 for the vertical shaft 21, which has keyed thereto the gear 22 rotatably mounted in the frame extension 8'.

The motor shaft 23 is provided with a pinion 24, which meshes with the spur gear 25, and secured to the latter is a bevel gear 26 meshing with the horizontal bevel gear 27. The latter is keyed to the vertical shaft 28 under the cap plate 29. Keyed to the vertical shaft 28 is a spur gear 30, which 100 meshes with another spur gear 31 on the vertical shaft 32, and the gear 31 meshes with the gear 22.

It will thus be seen that upon the operation of the motor 9, power may be transmitted at reduced speed to the vertical shaft 21.

The base frame 18 is provided at its up-

per portion with a large cylindrical bearing 33, on which is rotatably mounted the hub 34. Extending radially from this hub is an arm 35, on the outer end of which is secured the dislodging mechanism shown in Figs. 1, 3 and 4. It is preferred that this dislodging mechanism be detachable from the arm 35 by means of the bolts shown at 36, 37 and 38 in Figs. 1, 3 and 4. The dislodging mechanism shown in Figs. 1, 3 and 4 preferably consists of a frame 39, to which are rigidly connected the spaced-apart digging and splitting tools 40 and 41 for effecting dislodgment of the larger masses of coal from the mine wall. Between the tools 40 and 41 are additional small tools 42 for trimming the irregularities of the surface left by the larger tools. In a similar manner the floor tools 43 may be provided for trimming the floor so as to have an approximately flat surface. While the tool 41 may be adjusted so as to move along the floor of the mine chamber and the tool 40 extended forwardly beyond the tool 41 as shown in Fig. 4, the uppermost dislodging tool 44 is preferably mounted so as to be adjustable in elevation. In order to effect this adjustment the tool 44 is mounted on an arm 45 pivotally connected at 46 between the bracket arms 47 and 48 extending from the frame 39. Secured to the arm 45 is an arcuate guide 49 extending along the arcuate guideway 50, as shown in Fig. 4. On the guide 49 are auxiliary scrapers 51 for trimming off the mine wall between the large dislodging tools 40 and 44. After the arm 45 has been moved on the pivot 46 so as to adjust the elevation of the dislodging tool 44, the arm 45 may be clamped to the brackets 47 and 48 by means of the bolt 52 and nut 53, as shown in Figs. 1 and 3.

Hydraulic mechanism may also be provided for shifting the position of the arm 45 relatively to the frame 39 and locking the arm in adjusted position. By referring to Fig. 4 it will be seen that a link 54 pivotally connects the arm 45 to the upper end of the plunger rod 55, to which is connected the piston 56 movable in the hydraulic cylinder 57. The mechanism for controlling this hydraulic mechanism for adjusting the position of the arm 45 is shown in Fig. 7 and will be more fully hereinafter described.

Pivotally connected to the arm 45 is a roof scraper comprising the plate 58 and the scraping tools 59, as shown in Figs. 1, 3 and 4. The roof scraper may be secured in adjusted position by means of the bolt 60, as shown in Figs. 1 and 3.

The feeding mechanism for securing arcuate movement of the dislodging mechanism on the upright axis of the cylindrical bearing 33 comprises an oscillating ring plate 61 and ratchet mechanism operated thereby.

Fitted on the upper circular extension 62 of

the hub 34 is a ratchet ring 63. It will be seen that the latter is provided with vertical slots or keyways 64 into which fit the vertical feathers or splines 65, as shown in Fig. 3. The ratchet ring 63 may therefore be removed and reversed in position relative to the direction of the teeth 66.

The pawl 67 is provided with a plurality of notches so as to engage at one time a corresponding number of teeth of the ratchet ring 63. The pawl is so mounted as to have its rear end provided with a very strong bearing 68 to resist the back thrust on the pawl 67 during the feeding operation. The spring 69 constantly urges the pawl into engagement with the ratchet teeth, but will yield sufficiently to permit restoring the dislodging mechanism to initial position. When the arm 35 reaches the limit of its feeding movement it will engage with the lever 70, which is pivoted at 71 so as to rotate the eccentric 72 and thereby push pin 73 against the pawl 67 and throw it out of engagement with the ratchet teeth 66, thus automatically limiting the feeding movement of the dislodging mechanism.

In order to operate the pawl and ratchet mechanism to effect feeding movement of the dislodging tools in an anti-clockwise direction as viewed in Fig. 3, mechanism is connected between the shaft 21 and the plate 61 to oscillate the latter. At the upper end of the shaft 21 is secured an eccentric 74 mounted in a slide plate 75, which fits in the rectangular opening 76 in the plate 61, as shown in Fig. 3. When the motor 9 is operated to effect rotation of the shaft 21, the rotation of the eccentric 74 will cause the plate 75 to move laterally from side to side and also longitudinally along the rectangular opening 76. The sidewise movement of the plate 75 will cause the plate 61 to oscillate and therefore the pawl 67 will be moved in feeding direction and retracted alternately, and in this manner a very powerful feeding movement is transmitted to the arm 35 to effect continuous arcuate forward movement of the dislodging tools 40, 41 and 44.

The loading apparatus comprises a receiving conveyer having a chain 77 with radial flights 78, mounted on the frame 79, which has a forward beveled scooping edge at 80, as shown in Fig. 2. The endless chain 77 travels along an arcuate groove 81 at 120 the forward end of the machine, as shown in Figs. 1 and 2. The forward end of the receiving conveyer is located adjacent the floor of the mine chamber, but at the sides it is inclined upwardly, as shown at 82 in Fig. 1, so as to be able to mesh with the sprocket wheel 83, which is secured to the lower end of the vertical shaft 21. When material is scooped from the floor or is otherwise received by the conveyer comprising

ing the flights 78, the latter move this material to the receiving end 84 of the loading conveyer 85, which may be of the endless chain scraper type as shown in Figs. 3 and 3a. The loading conveyer 85 may be supported on brackets 86 and 87 pivoted respectively at 88 and 89 to the main framework. As shown in Fig. 3a, the bracket 86 may be provided with a toe 90 for engaging the frame 8 to hold the bracket 86 in a substantially horizontal position. The bracket 87 may be provided with a similar limiting device. It should be understood that the brackets 86 and 87 are movable so that the loading conveyer may be placed in the position shown in dotted lines in Fig. 6 when the dislodging mechanism is swung to the right angle position shown in dotted lines in this view.

It should be noted that the conveyer frame 79 is semi-circular in plan view and pivoted to the sides of the base frame, as illustrated at 200 in Fig. 1. The bottom of the semi-circular frame 79 is flat and the frame itself is comparatively thin so that the conveyer flights 78 will operate close to the mine floor. The forward beveled edge 80 will therefore be free to move along the floor so as to move under material on the floor which will hold the bottom of the conveyer frame 79 against the floor, particularly when the whole machine is moved forward by the rear jack 113. While the flights 78 are adapted to be operated so as to move scooped up material onto the receiving end 84 of the conveyer 85, such flights may be reversed when desired to move the cuttings or slack coal off to one side of the machine between the incline 82 and the jack 112. By reason of the pivotal connection of the links 78 to the chain 77 the semi-circular frame 79 may be tilted up and down relatively to the frame 18 on the pivot 200 without interfering with the operation of such flights. Furthermore, the guide groove 81 holds the chain down so that the flights 78 will move along the conveyer trough immediately back of the beveled surface 80.

When the apparatus is in the position shown in Fig. 3 the loading conveyer may also receive support from the wall jack 91, but I prefer to provide the detachable horizontal brackets 86 and 87, so that the loading conveyer can be supported independently of the wall jack 91.

After the dislodging mechanism has made a complete semi-circular feeding movement in an anti-clockwise direction as viewed in Fig. 3 and the limit stop mechanism has discontinued further feeding automatically, the clutch 92 may be operated by means of the lever 93, which is detachably connected at 94 to the rock shaft 95 which extends entirely across the casting 17. By adding the squared projection 94 on both sides of the

machine the lever 93 may be connected to the rod 95 from either side when the machine is in the position shown in Fig. 3. When the machine is in the position shown in dotted lines in Fig. 6 the lever 93 may be applied to that side shown in Fig. 1.

The clutch element 92 is splined to the depending shaft 96, which is secured to the shaft 21. When the other clutch element 97 is engaged by the clutch element 92, power will be transmitted from the shaft 21 to the gear 98 which meshes with the gear 99. The latter is secured to the vertical shaft 100, which carries the gear 101 when the latter is in mesh with the gear 102. The latter gear is journaled on the cylindrical bearing 103, which is mounted in the castings 19 and 104. It should be understood that the castings 12 and 19 are rigidly secured together by means of the bolt 105, and that the castings 104 and 17 are rigidly secured to the castings 19 and 12, so that these castings together with the base frame 18 become parts of the supplemental frame which is rotated bodily on the shaft 21 as a vertical axis. When the gear 102 is rotated it effects rotation of the arm 35 by reason of the gear 106 which is in mesh with the gear 102.

For operation of the pawl and ratchet mechanism it is preferred that the motor 10 be rotated so that the eccentric 74 will be moved anti-clockwise as viewed in Fig. 3, because then the plate 61 will be oscillated to move the pawl 67 in feeding direction when the eccentric 74 has the greater leverage relatively to the center of the upright axis of the cylindrical bearing 33. When the eccentric 74 is rotated anti-clockwise as viewed in Figs. 2 and 3, the gear 106 will be rotated clockwise to effect the proper restoring movement to the dislodging mechanism.

After the main frame 8 and the supplemental frame 18 are moved to the desired position for operation of the dislodging mechanism, a hydraulic roof jack is operated to secure anchoring of the frame 18. In the cylindrical bearing 33 is located a large plunger 107 having a semi-spherical bottom as shown in Fig. 2. A gasket 108 may be placed at the upper inner portion of the cylinder 33. Connected to the upper central portion of the plunger 107 in a semi-spherical recess is a semi-spherical support 109 for the shoe 110, which has upper horizontal serrated surfaces 111. It will thus be seen that when the plunger 107 is moved upwardly by hydraulic power the shoe 110 will engage the roof and by reason of the semi-spherical connection at 109 the shoe will automatically adjust itself to irregularities of the surface of the roof. When the hydraulic jack is operated by hydraulic power the frame 18 with the castings 12, 19, 17 and 104 are securely anchored in position.

between the floor and roof of the mine chamber.

In order to resist any tendency which the machine may have to swerve out of its adjusted position during the operation of the dislodging mechanism, wall jacks are provided such as those shown at 91, 112 and 113. The wall jack 112 is pivotally connected between the ears 115 in Fig. 3, but may be disconnected therefrom and connected pivotally to the ears 116 when desired. In the same manner the jack 113 may be pivotally connected to the ears 117 at one corner of the rear frame 11 or to the ears 118 at the rear end of the frame 11. In Fig. 3 the wall jack 112 is shown in dotted line position in engagement with one of the side walls, but it should be understood that the outer end of this hydraulic jack is provided with a roof jack at 120. In a similar manner a hydraulic jack 113 is provided with a roof jack 121. Each of the jacks 91, 112 and 113 comprises a cylinder with a piston therein, this piston being connected to a wall engaging shoe or a vertical roof jack. When the wall jack 91 is in the position shown in Fig. 3 it would resist a tendency of the machine to swerve toward the wall 122 when the dislodging mechanism is moved in a reverse direction, that is, in an anti-clockwise direction as viewed in Fig. 3. If the dislodging mechanism is reversed so as to operate in a clockwise direction the wall jack 91 could be placed on the opposite side of the main frame. By placing the wall jack 112 between the wall 122 and the ears 116, the forward portion of the machine could be moved laterally when the roof jack 110 is released. In a similar manner, when the wall jack 112 is in the dotted line position 119, the machine may be moved away from the wall 123. When the hydraulic jacks 112 and 113 are in the position shown in full lines in Fig. 3 and the roof jacks 120 and 121 are in anchored position, the hydraulic jacks 112 and 113 may be operated to move the entire machine forward to a new position while the jacks 91 and 110 are released.

In Fig. 7 I have shown a hydraulic control system which may be used in connection with the machine shown in Figs. 1, 2 and 3. By referring to Fig. 2 it will be seen that at the lower end of the shaft 28 is an eccentric cam 124 surrounded by a strap 125, which is connected with the plunger 126 operating in cylinder 127 of a pump for supplying liquid pressure through the pipe 128. A supply tank for the liquid is shown at 129 in Fig. 7. When the plunger 126 moves to the right the check valve 130 is opened to effect suction of the water through the pipe 131 into the cylinder 127. When the plunger 126 is moved to the left, the check valve 132 is automatically opened and the check valve

130 closed. This will effect the discharge of the liquid under pressure into the pressure pipe 128 and thence through the various branch pipes 133, 134, 135, 136 and 137 to the valves 138, 139, 140, 141 and 142, respectively. There are also branch pipes 143 and 144 extended to the valves 145 and 146, respectively.

By operating the valves 141 and 142 the hydraulic motor for adjusting the position of the dislodging tool 44, shown in Fig. 4, may be operated. When the valves 141 and 142 are in the position shown in Fig. 7, the liquid under pressure is supplied through the pipe 137 to the cylinder 57 to move the piston 56 upwardly while the liquid above the piston 56 is discharged through the pipe 147 and the valve 141 into the pipe 148, which in turn discharges into the exhaust pipe 149 connected to the bottom of the tank 150. When the levers 151 and 152 are turned to such positions that the liquid can neither enter nor flow from the cylinder 57, the piston 56 will be locked in adjusted position. By turning the lever 151 to the right a quarter turn and the lever 152 to the left a quarter turn the liquid under pressure may be supplied through the pipe 136 to the cylinder 57 above the piston 56, and the liquid below the piston 56 may be connected to the exhaust pipe 149. In this manner the arm 45 may be moved in a downward direction.

Connected to the passageway 158 at the lower portion of the cylinder 33 is a pipe 154 leading to the valve 140. When the lever 155 is in the position shown in Fig. 7 the pipe 154 is connected to the pipe 156 and thence to the exhaust, but when the lever 155 is turned toward the right 90 degrees the pressure supply pipe 135 is connected to the cylinder 33 below the plunger 137 to effect upward movement thereof and the anchoring of the base frame between the floor and roof of the mine chamber.

An accumulator 157 is preferably connected to the pipe 154 between the valve 140 and the cylinder 33. This accumulator comprises a plunger 158 adapted to act against a strong spring 159, so that when the forward roof jack is in anchored position and the dislodging mechanism is operated, any tendency of the shoe 110 to yield in an upward direction will be immediately followed by the action of the accumulator in maintaining the desired pressure below the plunger 107 to hold the roof jack 110 firmly in anchored position. It should also be understood that when the lever 155 is moved to such a position that neither pipe 135 nor 156 is connected to the pipe 154, the plunger 107 will be locked in anchored position. Even then, however, the accumulator 157 will automatically move the plunger 107 upwardly a short distance within the capacity 130

of the accumulator, if the roof tends to yield slightly during the operation of the dislodging mechanism.

When the valve 138 is in the position shown in Fig. 7 the wall jack 91 may be operated to move the shoe 161 into contact with the wall 122, and by turning the lever 160 to the position shown in Fig. 7 the wall jack 91 may be locked in adjusted position. When the valve 145 is in the position shown in Fig. 7, liquid under pressure will be supplied to the pipe 143 and pipe 162 and thence to the cylinder of the hydraulic jack 113. The roof jack 121 is supplied with liquid pressure through the passageway 163 in the plunger 164, which is connected between the piston 165 and the cylinder 166. By turning the lever 167 to the right a quarter turn the piston 165 may be moved to the right because at the same time the plunger 168 of the roof jack 121 will be released. Thus it will be seen that the roof jack will be moved forwardly, and when the lever 167 is returned to the position shown in Fig. 7 the roof jack 121 will be anchored in its new position and that the frame to which the ears 117 are connected will be moved forwardly.

In a similar manner, the valve 146 may be used to control the hydraulic jack 112 and the roof jack 120 to move the frame step-by-step for use as an abutment to effect forward movement step-by-step of the frame to which the ears 115 are connected.

By referring to Fig. 1 it will be seen that the rear end of the machine is provided with an elevating jack 169 comprising a cylinder 170 and a plunger 171, as shown in Fig. 7. The upward and downward movement of this plunger 171 may be controlled by the valve 139, and by moving the lever 172 to valve-closing position the plunger 171 may be locked in adjusted position. In this manner the rear end of the machine may be adjusted in elevation, so as to incline the forward path of the machine upwardly or downwardly or to a horizontal position.

While I have shown the supply tank 129 diagrammatically in Fig. 7, I have shown in Fig. 5 compartments 173 and 174 for containing the liquid, the intake pipe being indicated at 131', the pressure supply pipe at 128 and the exhaust pipe connected at 149'. By comparing Figs. 2 and 5 it will be seen that a shaft 175 is mounted in journal bearings 176 and 177. The compartments 173 and 174 may be provided with cover plates 178 and 179.

In Fig. 6 is shown in dotted lines the positions of the various parts when the dislodging mechanism is adjusted on the vertical shaft 21 as an axis to occupy positions for dislodging material from the side walls.

It should be understood that the dislodging mechanism may be in a similar manner turned in the opposite direction for operation on the opposite mine wall. The conveyer 85 may be disconnected from the horizontal supports 86 and 87 and the latter disconnected from the machine so that the conveyer may occupy the dotted line position shown at 180 in Fig. 6. The jacks 112 and 113 may be pivotally connected at 114 and 116 and then operated to shift the whole machine toward the side wall 123 so that it will occupy the position shown by the dotted line 181. The dislodging mechanism may then operate along a path indicated by the dotted line 182. The jacks 112 and 113 may then be connected to the ears 115 and 118 to shift the whole machine toward the wall 122, so that the dislodging mechanism may operate along the successive paths indicated by the dotted and shaded lines 183, 184 and 185. When the dislodging mechanism is adjusted for operation in its dotted line position indicated at 186 in Fig. 6 the bolts 14 are inserted in the openings 13 to lock the supplemental frame 18 against arcuate movement relatively to the main frame 8 on the upright axis 21. Furthermore, when the dislodging mechanism is operating in its dotted line position shown in Fig. 6, the roof jack 110 is relied upon to hold the supplemental frame 18 in anchored position while the main frame 8 is kept from swerving by a wall jack or the horizontal hydraulic jack connected to an anchored roof jack.

Obviously those skilled in the art may make various changes in the details and arrangements of parts without departing from the spirit and scope of my invention as defined by the claims hereto appended, and I wish therefore not to be restricted to the precise construction herein disclosed.

Having fully described the invention and illustrated an embodiment thereof, what I desire to have secured by Letters Patent of the United States, is:

1. In a mining and loading machine, the combination with a main frame, of a conveyer having a forward semi-circular hinged frame to facilitate maintaining the receiving lip of the latter on the floor, dislodging mechanism mounted on said main frame, and a delivering conveyer in position for receiving material from said first-named conveyer.

2. In a mining and loading machine, the combination with a main frame, of a floor jack at the rear end thereof for adjusting the elevation of the latter, an endless flight conveyer comprising an arcuate receiving frame in scooping position at the floor and hinged to said frame to maintain such position when the elevation of the rear end of

1. said main frame is adjusted, and means mounted on said main frame for dislodging material from an upright mine wall into the path of said conveyer.
2. 3. In a mining machine, the combination with a main frame adapted to travel longitudinally along a mine chamber, of a supplemental frame, a joint between said supplemental frame and said main frame to permit lateral adjustment of said supplemental frame on the upright axis of said joint to positions extending toward the side walls of the mine chamber, dislodging mechanism mounted on said supplemental frame, means for locking said main and supplemental frames in adjusted angular relation, and means for operating said dislodging mechanism to dislodge coal from a mine wall at the head of the mine chamber when said frames are in alignment and to dislodge coal from the side walls when said supplemental frame is extended laterally relative to said main frame.
4. In a mining machine, the combination with a main frame, of a supplemental frame pivoted thereto, dislodging mechanism mounted on said supplemental frame to move bodily therewith, a detachable ratchet ring connected to said supplemental frame, and means connected to said ratchet ring for moving said supplemental frame continuously in the same direction to effect feeding of said dislodging mechanism.
5. In a mining machine, the combination with a main frame, of a supplemental frame pivoted thereto, dislodging mechanism mounted on said supplemental frame to move bodily therewith, means comprising pawl and ratchet mechanism for effecting feeding of said dislodging mechanism, and means for automatically limiting the feed of said dislodging mechanism by rendering inoperative the pawl and ratchet mechanism.
6. In a mining machine, the combination with a supporting frame, of a supplemental frame, dislodging mechanism mounted on said supplemental frame, a circular ratchet connected to said supplemental frame, a pawl for engaging said ratchet, a ring surrounding said ratchet and connected to said pawl to transmit power thereto, and means for oscillating said ring to reciprocate said pawl and effect feeding movement of said dislodging mechanism.
7. The combination with a main frame, of a supplemental frame, dislodging mechanism mounted on said supplemental frame to move bodily therewith, means for moving said supplemental frame in one direction to feed said dislodging mechanism, an automatic limit stop for said dislodging mechanism, and means comprising gearing connected to said supplemental frame and controlled by a manually operated clutch for quickly returning said supplemental frame to initial position to restore said dislodging mechanism.
8. In a mining and loading machine, the combination with a base frame having an upright standard, of a hub journaled on said standard, a radial arm extending from said hub, dislodging mechanism mounted on said radial arm to move bodily therewith, means for moving said hub pivotally on said standard to effect feeding movement of said dislodging mechanism, a conveyer frame narrow in thickness and having a flat bottom adapted to rest on the mine floor in advance of said base frame, a beveled periphery on the forward edge of said conveyer frame at the mine floor, and a flight conveyer mounted on said conveyer frame adjacent the floor back of said beveled periphery and in position to travel around the forward portion of said base frame under said radial arm, the space between the beveled periphery and the flight conveyer being free and unobstructed to permit said beveled periphery to scoop material from the floor and direct it onto said flight conveyer.
9. In a mining and loading machine, the combination with a main frame, of a supplemental frame mounted thereon to move arcuately relatively thereto on an upright axis, dislodging mechanism mounted on said supplemental frame to move bodily therewith on said upright axis, a conveyer frame connected to said main frame for yielding contact with the mine floor in advance of said main frame, a traveling conveyer extending around the forward end of said main frame on said conveyer frame along a semi-circular path concentric with said upright axis, and means for operating said dislodging mechanism to dislodge material into position to be received by said conveyer.
10. In a mining and loading machine, the combination with a main frame, of a supplemental frame mounted thereon for swinging movement on an upright axis, dislodging mechanism mounted on said supplemental frame to move therewith on said upright axis, an arcuate conveyer frame having pivotal connections with opposite sides of said main frame and adapted to yieldingly move over the mine floor, a conveyer on said conveyer frame having a forward arcuate path of travel around the forward end of said main frame, and a loading conveyer in position to receive material from said first-named conveyer.
11. In a mining and loading machine, the combination with a main frame, of means at the rear portion thereof for adjusting the elevation of the latter, a conveyer comprising a receiving frame in scooping position at the floor and pivoted to said frame to maintain such scooping position when the elevation of the rear end of said frame is ad-

justed, and means mounted on said main frame for dislodging material into position to be received by said conveyer.

12. In a mining machine, the combination with a main frame, of a supplemental frame pivoted thereto, dislodging mechanism mounted on said supplemental frame to move bodily therewith, means comprising pawl and ratchet mechanism for effecting feeding of said dislodging mechanism, means for automatically limiting the feed of said dislodging mechanism by rendering inoperative the pawl and ratchet mechanism, and means independent of said pawl and ratchet mechanism for restoring said dislodging mechanism to initial position.

13. In a mining machine, the combination with a frame comprising a hydraulic cylinder, of a plunger in said cylinder, a roof-engaging shoe on top of said plunger, means for controlling the flow of liquid into and out of said cylinder to control the application of said shoe to said roof, a hub journaled on said pivot to move pivotally relatively to said frame, a radial arm extending from said hub, dislodging mechanism mounted on said radial arm to move bodily therewith, a ratchet connected to said hub, a pawl for engaging said ratchet means for reciprocating said pawl to act on said ratchet to cause said frame and said dislodging mechanism to move in feeding direction, means for automatically limiting the feed of said dislodging mechanism by rendering inoperative the pawl and ratchet mechanism, and means independent of said pawl and ratchet mechanism for restoring said dislodging mechanism to initial position.

14. In a mining and loading machine, the combination with a main frame, of dislodging mechanism mounted thereon, a conveyer having a forward semi-circular hinged frame to facilitate maintaining the receiving lip of the latter on the floor, said conveyer having the rear portion thereof inclined upwardly from such semi-circular portion, and means for operating said conveyer for transferring toward loading position material dislodged by said dislodging mechanism.

15. In a mining machine, the combination with a main frame, of dislodging apparatus mounted thereon, a roof jack for said main frame, a wall jack for resisting twisting strains during the operation of said dislodging apparatus, a pivotal connection between said wall jack and the main frame for permitting swinging of said wall jack to a position lengthwise of the machine, and a roof jack abutment for said wall jack to act against when assisting in moving the machine forward.

16. In a mining machine, the combination with a main frame, of dislodging mechanism

mounted thereon, a plurality of horizontal jacks pivotally connected to said main frame to swing on upright axes, additional upright jacks connected to the outer ends of the horizontal jacks to act as abutments against which the horizontal jacks may act respectively, and an operating system for said jacks comprising means for independently controlling the horizontal jacks.

17. In a mining machine, the combination with a main frame, of dislodging apparatus mounted thereon, means for anchoring said main frame to hold the same stationary during the operation of said dislodging apparatus, a wall jack for resisting twisting strains during the operation of said dislodging apparatus, a connection between said wall and the main frame for permitting adjustment of the wall jack to a position lengthwise of the machine, and a roof jack to serve as an abutment for said wall jack to act against when assisting in moving the machine forward.

18. In a mining machine, the combination with a main frame, of a supplemental frame connected thereto to extend in advance thereof along a mine chamber and substantially parallel to the walls of the latter, a joint between the main and supplemental frames for adjustment of the supplemental frame relative to said main frame on an upright axis, means for securing said frame against relative movement after being placed in relatively adjusted position, a motor on said main frame, dislodging mechanism mounted on said supplemental frame in position to dislodge a crescent-shape mass of coal from the solid face of a mine vein over an area extending from the floor to the roof of the mine chamber, and power transmitting mechanism between said motor and said dislodging mechanism for operating the latter while said supplemental frame is being held in adjusted position relative to said main frame and rigidly connected to the latter.

19. In a mining machine, the combination with supporting framework, of dislodging mechanism mounted thereon comprising pointed wedging tools arranged in upright spaced-apart relation and adapted to move continuously forward during operation to penetrate the solid coal of the face of the mine vein and by wedging action split large portions of the coal from such face over a wide area between the floor and roof, hydraulic mechanism for powerfully anchoring said supporting framework to hold the same stationary during the operation of said dislodging mechanism, means for operating said dislodging mechanism by moving such tools continuously forward while said frame is anchored to cause such dislodging mechanism to dislodge the coal from its native bed in large pieces over such wide area

of the face of the mine vein, and means comprising a hydraulic motor mounted on said framework for operating said anchoring mechanism.

5 20. In a mining machine, the combination with supporting framework, of a hydraulic roof jack therefor, an accumulator connected to said roof jack and adapted to permit said roof jack to yield or expand in accordance with sagging or yielding of the roof, means for controlling the operation of said roof jack, dislodging mechanism mounted on said supporting framework for feeding movement relatively thereto, and means for 15 operating said dislodging mechanism while said roof jack anchors said supporting frame and while said accumulator remains connected to said roof jack to take up variations in the roof during the operation of said dislodging mechanism.

21. In a mining machine, the combination with a main frame, of a supplemental frame pivoted thereto for relative adjustment on an upright axis, means comprising a key for 25 securing said frames rigidly together in adjusted angular relation to prevent said supplemental frame from being moved relatively to said main frame, dislodging mechanism mounted on said supplemental frame, and means comprising a motor on said main frame and an upright shaft at said upright axis for operating said dislodging mechanism while said main and supplemental frames are rigidly connected together in 30 such adjusted relation.

22. In a mining machine, the combination with supporting framework, of a hydraulic roof jack therefor, means for controlling said roof jack, an accumulator connected 40 directly to said roof jack, dislodging mechanism mounted on said supporting framework for feeding movement relatively thereto, and means for operating said dislodging mechanism while said roof jack anchors said framework and while said accumulator compensates for variation in roof level at the 45 roof jack.

23. In a mining machine, the combination with a main frame, of dislodging apparatus 50 mounted thereon, a horizontally extending wall jack pivotally connected to said main frame for movement to a position extending longitudinally of the machine, and an upright roof jack at the outer end of said wall jack to act as an abutment for the latter when in such longitudinal position and operated to move the machine forward.

24. In a mining machine for low roof mine chambers, the combination with a main frame, of a supplemental frame having substantially the same height as said main frame and pivotally connected to said main frame for adjustment relative to the latter on an upright axis, means for securing said

frames rigidly together in adjusted angular 65 relation to prevent said supplemental frame from being moved relatively to said main frame, dislodging mechanism mounted on said supplemental frame, and power transmission gearing comprising an upright shaft 70 at said upright axis for operating said dislodging mechanism while said frames are so held in fixed and rigid relation.

25. In a mining machine, the combination with a main frame adapted to rest on and slide over a mine floor, of a supplemental frame also adapted to rest on and slide over a mine floor, a joint between said main and supplemental frames to permit adjustment of said supplemental frame on an upright 80 axis of said joint to positions extending toward the side walls of the mine chamber, means for holding the frames rigidly connected in adjusted positions, dislodging mechanism mounted on said supplemental 85 frame for arcuate feeding movement relatively thereto in advance of said upright axis, and means for operating said dislodging mechanism to dislodge material from an upright mine wall at the head of the mine 90 chamber when said frames are in alinement with each other and to dislodge material from the upright side walls when said supplemental frame is extended laterally relative to said main frame and both of said 95 frames are resting on the mine floor.

26. In a mining and loading machine, the combination with a main frame, of a traveling flight conveyor comprising a frame and flights traveling along the latter in an arcuate path around the forward end of said main frame, means for yieldingly supporting said conveyor frame on said main frame for yielding contact with the floor in advance of said main frame when said main conveyor is moved rectilinearly along the 100 floor, means for imparting a rectilinear movement to said conveyor to cause its frame to scoop material from the floor while in such yielding contact therewith and while 105 said flights travel arcuately along the conveyor frame around the forward end of said main frame, and means for driving said conveyor to impart such arcuate movement to 110 said flights.

27. In a mining machine, the combination with a main frame adapted to occupy a stationary position in a mine chamber, of a supplemental frame pivotally connected to said main frame for adjustment relative to 120 the latter on an upright axis, means for rigidly connecting said main and supplemental frames in adjusted angular relation relative to such upright axis, dislodging mechanism mounted on said supplemental 125 frame for feeding movement on an upright axis spaced from the first-named upright axis, and means for operating said dislodg-

- ing mechanism on its upright axis while said main and supplemental frames remain stationary.
28. In a mining machine, the combination with supporting framework, of a radial arm supported thereon for arcuate travel relatively thereto, dislodging mechanism comprising coal splitting tools adapted to be adjusted along said radial arm, means for holding said dislodging mechanism in adjusted position relative to said arm to move bodily therewith, and means for moving said arm arcuately relatively to said supporting framework to operate said dislodging mechanism.
29. In a mining machine, the combination with supporting framework, of a radial arm mounted on said framework for arcuate movement relatively thereto, dislodging mechanism comprising splitting tools slideable along said arm for adjustment relative thereto, means for holding said dislodging mechanism in adjusted position by rigidly connecting the same to said arm to adjust the radius of movement of such splitting tools, and means for arcuately moving said arm to operate said dislodging mechanism.
30. In a mining machine, the combination with supporting framework, of a radial arm mounted thereon for arcuate movement relatively thereto on an upright axis, coal splitting mechanism mounted on said arm for sliding adjustment along the same, means for holding said coal splitting mechanism rigidly connected to said arm in adjusted position relative thereto to adjust the radius of movement of said coal splitting mechanism, and means for swinging said arm on said upright axis to move said coal splitting mechanism therewith to operate the same along an upright mine wall.
31. In a mining machine, the combination with a main frame, of a supplemental frame pivoted thereto on an upright axis for adjustment to positions in advance of said main frame and to either side of the forward end thereof, dislodging mechanism mounted on said supplemental frame and adjustable bodily therewith to positions in advance of the main frame and to either side of the forward end thereof, means for holding the supplemental frame together with the dislodging mechanism in adjusted position in advance of the main frame or to either side of the forward end thereof, feeding means for said dislodging mechanism, a motor on the main frame, and power transmission gearing comprising an upright shaft on said upright axis connected between said motor and said feeding means to effect the operation of said dislodging mechanism in its various positions of adjustment in advance of the main frame or to either side of the forward end thereof.
32. In a mining machine, the combination with a main frame, of a motor on said main frame, a supplemental frame pivotally connected to said main frame for adjustment relative to the latter on an upright axis to positions in advance of the main frame and at either side of the forward end thereof, dislodging mechanism mounted on said supplemental frame for feeding movement on an upright axis spaced from said first-named upright axis, means for locking the main and supplemental frames in adjusted angular relation, and power transmission gearing between the motor on the main frame and said dislodging mechanism on the supplemental frame, said power transmission gearing comprising an upright shaft located at the upright axis between said main and supplemental frames.
33. In a mining and loading machine, the combination with a main frame, of a conveyer having a semi-circular forward frame, pivotally connected to said main frame at the sides thereof on a transverse axis, having a fixed relation therewith to facilitate maintaining the semi-circular receiving lip of the conveyer frame on the floor in advance of said main frame, dislodging mechanism mounted on said main frame for arcuate movement relatively thereto in position to dislodge material to be received by the forward semi-circular portion of said conveyer, and means for operating said conveyer.
34. In a mining and loading machine, the combination with a main frame, of a conveyer having a forward semi-circular frame pivotally connected to the sides of said main frame on a transverse axis having a fixed relation thereto for yielding movement over the floor in advance of said main frame, and dislodging mechanism mounted on said main frame for semi-circular movement relatively thereto for dislodging material from an upright mine wall into position to be received by the forward semi-circular portion of said conveyer.
35. In a mining and loading machine, the combination with a main frame having a forward semi-circular face at its base, of a conveyer having a semi-circular frame at its forward portion pivotally connected to said main frame at the sides of the latter and near its semi-circular base on a transverse axis spaced back from the forward end of said main frame to facilitate maintaining the receiving lip of the semi-circular portion of the conveyer frame on the floor in advance of said main frame, dislodging mechanism mounted on said main frame for arcuate movement relatively thereto in position to facilitate dislodging material from an upright mine wall to be received by the forward portion of said conveyer, and means for operating said conveyer.
36. In a mining machine, the combination

with a supporting frame, of a supplemental frame mounted thereon for pivotal movement relatively thereto on an upright axis, a series of spaced-apart penetrating wedging tools mounted on said supplemental frame to move bodily therewith and adapted to penetrate the solid face of the mine vein and by wedging action split large pieces of mineral therefrom, a roof jack for the forward portion of said supporting frame, means for swinging said supplemental frame on said upright axis as a pivot to operate said tools while the forward portion of said supporting frame is anchored by said roof jack, and a jack abutment connected to one side of the rear portion of said supporting frame to prevent swerving of the said supporting frame during the operation of said tools.

37. In a mining machine, the combination with a main frame, of a roof jack mounted on the forward portion of said frame, a supplemental frame pivoted to said main frame for swinging movement on the upright axis of said roof jack, a plurality of penetrating wedging tools mounted on said supplemental frame in spaced-apart relation and each adapted to penetrate the solid coal face of the mine vein and by wedging action tear large pieces of coal from the unmined mass, and means mounted on said main frame and connected to said supplemental frame for swinging said supplemental frame while said roof jack is anchored, to exert sufficient force on said tools continuously forward into the solid coal face to split large pieces of coal therefrom between the floor and the roof of the mine chamber while said main frame remains stationary.

38. In a mining machine, the combination with a main frame, of a roof jack for very firmly and powerfully anchoring the forward portion of said main frame in fixed position, a supplemental frame mounted on the forward portion of said main frame for pivotal swinging movement relatively thereto on an upright axis, claw-like dislodging mechanism mounted on said supplemental frame to move bodily therewith and adapted to penetrate the solid coal in its native bed and by wedging action split the coal from the mine vein in large pieces over a wide area, means for operating said dislodging mechanism by swinging it continuously forward on said pivotal upright axis and relatively to said framework while the latter remains anchored, to effect tearing away of the coal from the mine vein in large pieces, and an abutment device for one side of said main frame to resist swerving of the latter during operation of said dislodging mechanism.

39. In a mining machine, the combination with a main frame, of a supplemental frame movable relatively thereto, a hydraulic roof jack for very powerfully anchoring the for-

ward portion of said main frame in fixed and in immovable position, dislodging mechanism secured rigidly to said supplemental frame for bodily movement therewith and comprising a plurality of spaced-apart claw-like penetrating tools each adapted to enter the coal in its native bed and by wedging action split the coal in large pieces from the mine vein over a wide area extending between the said tools and above and below the same, said dislodging mechanism being immovable relatively to said supplemental frame, means for moving said supplemental frame relatively to said main frame while the latter remains in anchored position, to effect feeding movement of said dislodging mechanism and causing the latter to pierce and wedge the coal in large pieces over a wide area from the mine wall during the continuous forward movement across the mine wall, and a plurality of jack abutments connected to the sides of said main frame to prevent swerving thereof during the operation of said dislodging mechanism.

40. In a mining machine, the combination with a main frame, of a roof jack for anchoring the forward portion of said main frame, a supplemental frame mounted on said main frame for arcuate movement relatively thereto, dislodging mechanism comprising claw-like spaced-apart pointed wedging tools connected together in rigid relation and rigidly connected to said supplemental frame for bodily movement therewith, said claw-like dislodging tools being adapted to engage the solid face of the mineral in its native bed continuously while being fed arcuately along the same, means for operating said dislodging mechanism including arcuate movement of said supplemental frame to effect arcuate feeding of said dislodging mechanism with a continuous forward movement to cause said spaced-apart pointed wedging tools to penetrate the solid face of the mine vein and by wedging action split large pieces of the mineral from the unmined mass, and a wall jack connected to one side of said main frame at the rear portion thereof to serve as an abutment to resist swerving of the said frame during the operation of said dislodging mechanism.

41. In a mining machine, the combination with a main frame, of a roof jack for anchoring the forward portion of said main frame, a supplemental frame connected to the forward end of said main frame for arcuate movement relatively thereto on the upright axis of said roof jack, dislodging mechanism comprising spaced-apart penetrating wedging tools rigidly connected to said supplemental frame to move bodily therewith and adapted to penetrate the solid coal face in its native state to tear large pieces of coal therefrom by wedging action over a wide area extending from the floor to

the roof of the mine chamber, means for imparting arcuate movement to said supplemental frame to effect feeding of said dislodging mechanism while said main frame remains anchored, and a wall jack pivoted to the rear portion of said main frame on that side opposite the initial feeding position of said dislodging mechanism, to serve as an abutment to prevent swerving 10 of the main frame during the operation of said dislodging mechanism.

42. In a mining machine, the combination with a main frame having an upright cylindrical bearing on its forward end, of a supplemental frame having a hub pivotally mounted on said cylindrical bearing for arcuate movement relatively to the main frame on an upright axis, dislodging mechanism mounted on said supplemental frame for movement bodily therewith while rigidly connected thereto against movement either up or down and for continuous engagement with a mine vein during continuous forward feeding movement through an angle of about 25 180° from one side of the mine chamber to the other, means for confining said hub against up or down movement on said cylindrical bearing, means for swinging said supplemental frame relatively to said main frame through an arc of approximately 180° to effect the operation of said dislodging mechanism while said main frame remains stationary, and abutment mechanism at one side of the main frame near said upright axis to resist lateral movement of said cylindrical bearing during operation of said dislodging mechanism on the mine wall.

43. In a mining machine, the combination with a main frame, of a supplemental frame mounted on said main frame for swinging movement relatively thereto on an upright axis, dislodging mechanism mounted on said supplemental frame to move bodily therewith, means for operating the dislodging mechanism including the swinging of said supplemental frame to effect feeding, a roof jack for the forward portion of said main frame, a lateral abutment connected to the rear portion of said main frame at that side thereof opposite the starting position of said dislodging mechanism to resist swerving during the operation of said dislodging mechanism, and an additional lateral abutment connected to that side of said main frame near the starting position of said dislodging mechanism and near said upright axis and near said roof jack to assist said roof jack to resist movement of said upright axis laterally during operation of said dislodging mechanism and while said first-named abutment is acting as such.

44. In a mining machine, the combination with a main frame, of an upwardly extending cylindrical bearing on the forward end 65 of said main frame, a hydraulic roof jack

extending upwardly from within said cylindrical bearing, a supplemental frame having a hub pivoted on said cylindrical bearing for arcuate movements relatively to the main frame on an upright axis extending through 70 said roof jack, dislodging mechanism rigidly connected throughout to said supplemental frame to be stationary relative thereto in all directions but movable bodily with said supplemental frame through an arc of approximately 180° while said main frame remains stationary, means for swinging said supplemental frame on said upright cylindrical bearing to operate said dislodging mechanism on the solid coal face of a mine 80 vein, and abutment mechanism connected to one side of said main frame near said upright axis in position to resist the tendency of the main frame to swing about said upright axis during the operation of said dislodging mechanism.

45. In a mining machine, the combination with an elongated main frame, of a roof jack for the forward portion of said main frame, a supplemental frame mounted on said main frame for swinging movement relatively thereto on the upright axis of said roof jack, dislodging mechanism rigidly connected throughout to said supplemental frame so as to be stationary relatively thereto in all directions but movable bodily therewith, said dislodging mechanism comprising means to penetrate the face of the coal in its solid native state and tear the coal from the unmined mass in large pieces over a wide area extending from the floor to the roof of the mine chamber, means for swinging said supplemental frame on said upright axis to operate said dislodging mechanism while said roof jack is in anchored position, 105 a wall jack connected to the rear portion of said main frame at that side thereof opposite the initial position of said dislodging mechanism, and an additional wall jack connected to the other side of said main frame near the initial position of said dislodging mechanism.

46. In a mining machine, the combination with supporting framework, of a supplemental frame mounted on said supporting framework for swinging movement relatively thereto and comprising a radial arm, dislodging mechanism mounted on said arm for adjustment along the same to varying distances from the axis of swinging movement of the supplemental frame but rigidly connected thereto in adjusted position for bodily movement therewith, and means for swinging said supplemental frame to feed said dislodging mechanism at its adjusted 115 distance from the axis of swinging movement.

47. In a mining machine, the combination with an elongated supporting frame, of a supplemental frame comprising an arm, dis- 130

lodging mechanism rigidly connected to said arm with all of its parts stationary relatively to said dislodging mechanism, said dislodging mechanism being adapted to penetrate the solid face of the coal vein and split coal in large pieces therefrom over a wide area by a translating movement of said arm and said dislodging mechanism while the latter including all of its parts are rigidly connected to said arm against movement relatively thereto in any direction, means for guiding said arm through said translating movement to effect operation of said dislodging mechanism, a roof jack for the forward portion of said main frame, a horizontal jack abutment connected to one side of said main frame, a second horizontal jack abutment connected to the other side of said main frame, and a third horizontal jack abutment connected to the rear end of said main frame.

48. In a mining machine, the combination with a main frame, of a supplemental frame mounted thereon to swing relatively thereto on an upright axis and comprising a radial arm, splitting tools adapted to penetrate the solid face of a mine vein and split the mineral therefrom in large pieces, an auxiliary frame for said splitting tools, said auxiliary frame together with said splitting tools being slidable along said radial arm for adjustment to varying distances from said upright axis, means for securing said splitting tools rigidly to said arm at an adjusted distance from said axis for bodily movement with said arm along an arcuate path, and means for swinging said radial arm to operate said splitting tools while rigidly connected to said arm.

49. In a mining machine, the combination with a main frame, of a supplemental frame mounted thereon for swinging movement relatively thereto, dislodging mechanism mounted on said supplemental frame for bodily movement therewith and adapted to penetrate the solid face of a mine vein and split the mineral therefrom, a yoke, a reciprocating plate in said yoke, an eccentric for reciprocating said yoke, feeding means for powerfully swinging said supplemental frame relatively to said main frame to secure operation of said dislodging mechanism, and means for rotating said eccentric to secure the operation of said feeding means by the reciprocation of said plate in said yoke and the oscillation laterally of said plate and yoke.

50. In a mining machine, the combination with a main frame, of a supplemental frame mounted thereon for swinging movement relatively thereto on an upright axis, dislodging mechanism mounted on said supplemental frame for movement bodily therewith and adapted to act on the solid upright coal face to split large pieces of coal there-

from, a vertical driven shaft, an eccentric thereon, a yoke, a plate slidable in said yoke and connected to said eccentric, and feeding mechanism connected to said yoke for operation thereby when said shaft is rotated to cause said eccentric to reciprocate said plate in said yoke both laterally and longitudinally of the machine, said feeding mechanism being connected to said supplemental frame to swing the latter on said upright axis to effect the operation of said dislodging mechanism.

51. In a mining machine, the combination with a main frame, of a supplemental frame mounted thereon to swing relatively thereto on an upright axis, a ratchet ring on said supplemental frame, a separate ring associated with said ratchet ring, pawl mechanism connected to said separate ring for driving said ratchet ring, mining mechanism connected to said supplemental frame in position to operate on an upright mine wall, and means for oscillating said ring to cause said pawl mechanism to drive said ratchet ring and feed said mining mechanism.

52. In a mining machine, the combination with a main frame adapted to be supported on a mine floor, of a supplemental frame mounted on said main frame for movement relatively thereto, dislodging mechanism carried by said supplemental frame in position to operate on an upright mine wall adjacent said main frame, oscillating driving mechanism comprising a ring, and clutch mechanism within said ring and between the same and said supplemental frame to transmit motion to the latter only in one direction.

53. In a mining machine, the combination with a main frame, of a supplemental frame, dislodging mechanism on said supplemental frame to move bodily therewith in position to operate on an upright mine wall while said main frame is supported on the mine floor, reciprocating driving mechanism, and a ring clutch between said driving mechanism and said supplemental frame for imparting step-by-step forward movement always in the same direction to effect feeding of said dislodging mechanism.

54. In a mining machine, the combination with a main frame, of a supplemental frame mounted thereon to swing relatively thereto on an upright axis and comprising a radial arm, a claw-like penetrating tool adapted to pierce the solid face of a mine vein and split large pieces of coal therefrom above and below the path of said tool, said tool being slidable along said radial arm to various distances from the axis of swinging movement of said supplemental frame, means for securing said penetrating tool rigidly to said arm at its adjusted distance from the axis of swinging movement of the supplemental frame for bodily movement

with said arm along an arcuate path, and means for swinging said radial arm to cause said tool in its adjusted position to dislodge the coal by a penetrating wedging action.

55. In a mining machine, the combination with a main frame, of a supplemental frame mounted thereon for swinging movement relatively thereto on an upright axis and comprising a hub concentric with said axis, a radial arm on said hub, dislodging mechanism carried bodily by said arm and comprising a plurality of spaced-apart penetrating wedging tools each adapted to pierce the solid face of a coal vein and split large pieces of coal from the unmined mass over a wide area, and pawl and ratchet mechanism associated with said hub for swinging said arm to operate said dislodging mechanism while said main frame remains stationary.

56. In a mining machine, the combination with supporting framework adapted to be supported on a mine floor near an upright working face of a coal vein, of a plurality of pointed penetrating tools each adapted to pierce such working face and by wedging action split the coal therefrom over a wide area and in large pieces, feeding means for said penetrating tools, a yoke, a reciprocating plate in said yoke, an eccentric for reciprocating said plate and oscillating said yoke to effect the operation of said feeding means, and mechanism on said supporting framework for rotating said eccentric.

57. In a mining machine, the combination with supporting framework adapted to be supported on a mine floor, of dislodging mechanism mounted on said framework for operation on an upright mine wall in advance of said framework while the latter is supported on the mine floor, a driven shaft mounted on said framework, an eccentric thereon, a yoke, a plate slidable in said yoke and connected to said eccentric, and feeding means for the dislodging mechanism connected to said yoke for operation thereby when said shaft is rotated to cause said eccentric to reciprocate said plate and oscillate said yoke.

58. In a mining machine, the combination with a main frame, of a supplemental frame mounted thereon to swing relatively thereto, a ratchet ring on said supplemental frame, a separate ring, pawl mechanism connected to said separate ring for driving said ratchet ring, dislodging mechanism mounted on said supplemental frame, and means for oscillating said separate ring to cause said pawl mechanism to drive said ratchet ring and feed said dislodging mechanism.

59. In a mining machine, the combination with a main frame, of a supplemental frame mounted on said main frame for arcuate movement relatively thereto, dislodging mechanism mounted on said supplemental

frame for bodily movement therewith, mechanism comprising pawl and ratchet means for swinging said supplemental frame to effect feeding of said dislodging mechanism, and automatic limit mechanism for rendering inoperative the ratchet means to effect automatic stopping of the feed of said dislodging mechanism.

60. In a mining machine, the combination with a main frame, of a supplemental frame mounted thereon for arcuate movement relatively thereto on an upright axis, dislodging mechanism at the outer end of said supplemental frame in position to operate on an upright mine wall horizontally in advance of said main frame, power transmission apparatus comprising vibratory mechanism, and clutch mechanism operable by said vibratory mechanism to effect a step-by-step but continuously forward feed to said supplemental frame to operate said dislodging mechanism.

61. In a mining machine, the combination with a supporting frame, of mining mechanism mounted thereon for operation on an upright mine wall horizontally in advance of said frame, feeding means for said mining mechanism, a yoke, a reciprocating plate in said yoke, an eccentric for oscillating said yoke, and means for rotating said eccentric to secure the operation of said feeding means by the reciprocation of said plate in said yoke and the oscillation of said plate and said yoke while said mining mechanism operates horizontally in advance of said supporting frame.

62. In a mining and loading machine, digging mechanism, framework for supporting said digging mechanism for arcuate movement along an upright mine wall, means for pushing said digging mechanism to dislodge material from such upright mine wall, and loading apparatus for automatically receiving the dislodged material and transferring such dislodged material to loading position.

63. In a mining and loading machine, the combination with a main frame, of a supplemental frame connected to said main frame to swing on an upright axis, multiple digging mechanism mounted at the outer end of said supplemental frame to have an arcuate path of travel when said supplemental frame is swung on said upright axis, means for swinging said supplemental frame to effect the operation of said digging mechanism to dislodge material along an arcuate upright mine wall, and loading apparatus comprising a conveyer with a receiving end adjacent said dislodging mechanism and in advance thereof.

64. In a mining machine, the combination with a frame movable laterally along a coal face, dislodging mechanism mounted on said frame, a conveyer extending in operation from points outside the coal face to the base

of the mine wall in advance of said dislodging mechanism, a plate arranged to move beneath the dislodged material, means for causing said plate to deliver dislodged material to said conveyer, and motor mechanism for operating said dislodging mechanism.

65. In a mining machine, the combination with a supporting frame, of roof jack mechanism for anchoring the same, wall abutment mechanism for the rear portion of said frame, arc-wall coal-stripping mechanism comprising widely spread-apart, claw-like penetrating fingers grouped in an upward series in position to rip and tear the coal in large pieces from the solid upright coal face of the mine vein, means for operating said coal-stripping mechanism by feeding said fingers arcuately, and additional wall abutment mechanism located adjacent the starting position of said operating means.

66. In mining and loading apparatus, the combination with a supporting frame, of a conveyer telescoped over said supporting frame and having freedom of movement up and down at its forward portion relatively to said supporting frame to adapt it to rest on the mine floor while said supporting frame rests thereon, and means for operating said conveyer to transfer toward loading position dislodged material received thereby.

67. In a mining and loading machine, the combination with a main frame adapted to rest on and slide over a mine floor, of mining mechanism mounted thereon, a conveyer supported on said frame and having a forward portion fitting around the forward portion of said frame and adapted to rest on and slide over the mine floor and move up and down relatively to said supporting frame, and means for operating said conveyer to transfer toward loading position the material dislodged by said mining machine.

68. In mining and loading apparatus, the combination with a supporting frame adapted to rest on and slide over a mine floor, of a conveyer mounted on said supporting frame to extend around the forward portion thereof and having its forward end adapted to rest on and slide over the mine floor

while free for up and down sliding movements relatively to the forward end of said supporting frame so that the weights of the forward portion of said supporting frame and the forward portion of said conveyer will be supported by the floor independently, and means for operating said conveyer to transfer toward loading position dislodged material received thereby.

69. In mining and loading apparatus, the combination with a supporting frame, of mining mechanism thereon, a conveyer telescoping over said supporting frame and having freedom of movement up and down at its forward portion relatively to said supporting frame in position to receive material dislodged by said mining mechanism and to adapt said conveyer to rest on the mine floor while said supporting frame rests thereon, and means for operating said conveyer to transfer toward loading position the material dislodged by said mining mechanism.

70. In a mining machine, the combination with supporting framework, of dislodging mechanism mounted thereon comprising pointed wedging tools arranged in upright spaced-apart relation and adapted to move continuously forward during operation to penetrate the solid coal of the face of the mine vein and by wedging action split large portions of the coal from such face over a wide area between the floor and roof, hydraulic mechanism comprising a roof jack and a wall jack adjacent the roof jack for powerfully anchoring said supporting framework to hold the same stationary during the operation of said dislodging mechanism, means for operating said dislodging mechanism by moving such tools continuously forward while said frame is anchored to cause such dislodging mechanism to dislodge the coal from its native bed in large pieces over such wide area of the face of the mine vein, and means comprising a hydraulic motor mounted on said framework and connected to said anchoring mechanism to operate the same.

In testimony whereof I have signed my name to this specification on this 22nd day of October, 1921.

EDMUND C. MORGAN.
